No 162

Design for a Stove

Patented Dec 18th 1847.

Des. 162

Lucius O. Palmer, Utica, New York,

Letters Patent No. 162, dated 18th December 1847.

(Assigned to John F. Seymour.)

The Schedule referred to in these Letters Patent and making
part of the same.

To all whom it may concern. Be it known that I, Lucius
O. Palmer of the City of Utica in the County of Oneida and
State of New York have invented and produced a new and
original Design, shape, configuration and Pattern of Stove Plates
to be used in the manufacture of stoves; the nature of my in-
vention consists in the peculiar form and ornamental carved

Des 160

work of the outer surface of the cast iron plates forming the stove.
The feet or legs of the stove are somewhat in the shape of the letter P, the upper curve being scrolled on the outer edges with a flower - starting out from between the scrolls and running down onto the lower curve quite to the foot of the leg; the bottom plate of the stove contains in the center a sink or pan about one inch deep; around this sink and a foot inches from it on all sides the bottom is raised so as to form a perfect seat for the flanges of the four sides of the stove rising about one inch above & outside of the said flanges, the raised part then slopes downwards & outward to the outer edges of the bottom which is a plain half round moulding excepting on the front side of the stove where the bottom plate - extends out sufficiently to form a hearth; the raised & sloping part just described is ornamented with graceful curved lines, the corners & center ornamented with a rich bouquet of flowers; the hearth is ornamented with diamond and indented panel work edged with straight & curved half round mouldings. The front and back plates of the stove are ornamented with three Gothic arches, the widest and largest arch being in the center; between and on the inside of the caps of each side arch is diamond & indented work, while between the columns or shafts which support the caps a wreath of flowers is suspended; in the middle of the center arch two shafts rise surmounted with graceful scrolls, diamond and indented work being within the scroll & shafts while around is rich panel work; from the pinnacle of the center arch two scrolls heavily and richly carved rise out & rest on the top of the arch & from the lower termination of these scrolls a vine starts out passing under and within the cap of the arch supports a rich bunch of flowers which is suspended low enough to rest lightly upon the top of the scrolls within

B

the centre arch; the upper corners of those plates around the arches are ornamented with carved diamond & indented panel work which cannot be more particularly described but is accurately delineated and represented in the annexed drawing; the two end plates are ornamented with four shafts or columns which are surmounted and anchored with rich scrolls below the upper and above the lower scrolled arch is a rich bouquet of roses while outside of the shafts are wreath of flowers. The centre of the top is flat but raised in the shape of a parallelogram about three inches above the outer edge of the plate; the top is ornamented with graceful curves terminating with roses, and bouquets of flowers; the outside of this parallelogram slopes outwards and downward within two inches of the outer edge of the top plate; the slope is ornamented with richly carved scrolls, between which are roses and bouquets of flowers; the outer edge of the stove is flat but scrolled. The foregoing description cannot be more accurately expressed, but is correctly represented by the annexed drawing, and on the top of the stove, stands a vase as delineated therein.

What I claim as my invention and desire to secure by letters Patent is the Design, shape, configuration, style and ornamental carvings of the external surface of the plates.
